ARTICLE SEPARATING PACKAGES FOR FLAT ARTICLES SUCH AS SURGICAL SUPPLIES

Robert H. Pratt, Milwaukee, Wis., assignor to Laukhuff-Pratt Mfg. Corp., Milwaukee, Wis., a corporation of Wisconsin

Filed Dec. 7, 1959, Ser. No. 857,842

5 Claims. (Cl. 206—63.2)

This invention relates to improvements in article separating packages for flat articles such as surgical supplies.

Surgical sponges and like articles are often packaged in twos with the sponges superimposed in the package. One well known type of package has adhesively secured flaps intermediate the depth of the package which may be moved angularly away from the front of the package to permit gripping of the lower portion of the package between the thumb and the forefinger of one hand. The uppermost of the connected flaps may then be pulled upwardly by the other hand to open the package, the paper of the lower portion of the package protecting the sponges from contact with the fingers of the gripping hand. With this type of package there is a problem of separating the two sponges from each other for use one at a time. It is either necessary to remove both sponges simultaneously from the package with a forceps for later separation, or it is necessary to use two forceps to separate the sponges while held in the package. Both methods are inconvenient and time consuming.

It is a general object of the present invention to provide an improved package for holding a plurality of sponges or the like so constructed that it is a simple matter to remove one sponge from the package with one hand while the other sponge is still gripped in the other hand protected by the paper of the package.

A more specific object of the invention is to provide a package of the class described wherein there is an inwardly projecting pleat at the lower edge of the package with two fold portions, one accommodating the lower edge of one sponge and the other fold portion accommodating the lower edge of the other sponge. With this arrangement the forefinger of the left hand may be inserted in the pleat between the two folds at the bottom of the package, the thumb being on the outside of one fold and the third finger on the outside of the other fold. Then when the upper portion of the package is ripped open, one sponge may be readily removed while the fingers tightly grip the other sponge to prevent its being pulled out before it is needed.

A further object of the invention is to provide an improved method of wrapping superimposed flat articles, in a manner to facilitate individual removal in a sanitary manner.

Other objects of the invention are to provide a package which is relatively simple and inexpensive in construction, neat in appearance, sanitary, and well adapted for the purposes described.

With the above and other objects in view, the invention consists of the improved package, and all of its parts and combinations, as set forth in the claims, and all equivalents thereof.

In the accompanying drawing, illustrating one complete embodiment of the preferred form of the invention,

2

in which the same reference numerals designate the same parts in all of the views:

Fig. 1 is a perspective view of the improved package with the folds at the lower edge of the package separated and with the adhesively connected flaps lifted upwardly at an angle and slightly separated, parts of the package being broken away;

Fig. 2 is a sectional view taken approximately on the line 2—2 of Fig. 1;

Fig. 3 is an end edge view of the package in its unopened condition; and

Fig. 4 is a cross sectional view through the opened package showing how it is held just prior to removal of a sponge.

Referring more particularly to the drawing, the numeral 10 designates a single length of paper, preferably a relatively inexpensive, thin, non-transparent packaging paper such as white sulphite. The paper is preferably of a somewhat porous nature so that it can breathe. The upper edge of the package has a top fold 11 from one of the longitudinal edges of a bottom panel 12. The lower edge of the package has an inwardly projecting pleat comprising a lower fold portion, having a fold line 13, and an upper fold portion having a fold line 14, which portions are swingable to separated condition as in Fig. 2 on the hinge line 15 of the pleat. From the fold line 14 the paper of the package continues over the top of the package and part way up as at 16 to form a partial top panel, and then in a reverse direction as at 17 to provide a flap foldable on the line 18. The flap 17 is adhesively connected as at 19 to a tearing flap 20 which forms a continuation of another top panel portion 21 of the package. The side edges of the package are suitably connected or sealed as at 22 preferably by use of an adhesive, and the side edges of the fold portions are similarly sealed. The fold portion 14 is, however, left unconnected to the fold portion 13, so that it can easily be swung away as in Figs. 1 and 2 to permit insertion of a finger in the pleat between the folds 13 and 14.

In the illustrated embodiment of the invention the package contains two flat articles 23 and 24. These may be surgical sponges of the type commonly called "cover sponges." The lower portion of one of the sponges is accommodated within and protected on both sides by the fold 13, and the lower portion of the other sponge is accommodated in and protected on both sides by the fold 14. The paper forming the pleat which has the fold line 15 keeps these portions in permanently separated condition. The upper portions of the sponges are in superimposed relationship as in Fig. 2.

In use of the package, the folds 13 and 14 are spread as in Fig. 1, and the forefinger is inserted in the pleat as in Fig. 4, the thumb gripping the panel portion 16 and the third finger gripping the outer side of the bottom panel. With this arrangement, one sponge is gripped between the thumb and index finger and the other sponge is gripped between the index finger and third finger with paper protecting the sponges from the fingers. Next, the tearing flap portion 20 is gripped with the right hand and ripped open to the condition of Fig. 4 to expose the upper portion of the sponges. If the outer sponge is to be removed first, the nurse holding the package grips tightly with the index finger and third finger while loosening up with the thumb. The surgeon or another nurse may then readily remove the outer sponge by the use of a forceps, without having the second sponge come with it. The second sponge may then be held in this sanitary, protected manner, until the surgeon is ready for it.

In the type of package commonly used heretofore, the lower portions of both sponges were simultaneously

gripped. It was therefore very difficult if not impossible to remove one sponge without having the other one come with it.

With the present invention, both sponges are kept in perfectly sanitary condition until they are used, and the sponges are always kept separated from the fingers of the gripping hand by layers of paper.

While a package for two sponges has been illustrated and is the most common, it is entirely practical to package sponges in greater multiples with additional folds at the lower edge of the package.

The improved package may obviously be used for other items than sponges, wherever sanitation is a factor.

It is to be understood that the present invention is not to be limited to the exact details of construction shown and described, for obvious modifications will occur to persons skilled in the art.

What I claim is:

1. In a relatively flat sanitary package having a bottom panel of paper, a first top panel portion folded from one edge of said bottom panel and closing part only of the top of the package and having a top transversely extending tearing flap intermediate the depth of the package, a pleat projecting inwardly from and disposed above the opposite edge of the bottom panel and providing lower and upper fold portions, said upper fold portion having a top side extending toward said first mentioned top portion and providing a second top panel portion closing the rest of the top of the package and having a flap connected to said tearing flap, said flaps being normally in parallelism with and against said second top panel portion, a flat article in the package having part accommodated in and protected on both sides by said lower fold portion, and another flat article in said package having part accommodated in and protected on both sides by said upper fold portion whereby with the index finger of one hand inserted in said pleat and with other fingers of the same hand engaging the outside of said fold portions the articles are individually gripped in the fingers while the tearing flap is being pulled by the other hand to open the top of the package.

2. In a relatively flat sanitary package having a bottom panel of paper, a first top panel portion folded from one edge of said bottom panel and closing part only of the top of the package and having a top transversely extending tearing flap intermediate the depth of the package, a pleat projecting inwardly from and disposed above the opposite edge of the bottom panel and providing lower and upper fold portions, said upper fold portion having a top side extending toward said first mentioned top portion and providing a second top panel portion closing the rest of the top of the package and having a flap adhesively connected to said tearing flap with the latter having a free pulling portion outwardly of the adhesive connection between flaps, said flaps being normally in parallelism with and against said second top panel portion, a flat article in the package having part accommodated in and protected on both sides by said lower fold portion and another flat article in said package having part accommodated in and protected on both sides by said upper fold portion whereby with the index finger of one hand inserted in said pleat and with other fingers of the same hand engaging the outside of said fold portions the articles are individually gripped in the fingers while the tearing flap is being pulled by the other hand to open the top of the package.

3. In a relatively flat sanitary package having a bottom panel of paper, a first top panel portion folded from the upper edge of said bottom panel and closing part only

of the top of the package and having a top transversely extending tearing flap intermediate the depth of the package, means sealingly connecting the side edges of said bottom panel with corresponding portions of said top panel portion, a pleat projecting inwardly from and disposed above the lower edge of the bottom panel and providing lower and upper fold portions having sealingly connected side edges, said upper fold portion having a top side extending toward said first mentioned top portion and providing a second top panel portion closing the rest of the top of the package and having a flap secured to said tearing flap, said flaps being normally in parallelism with and against said second top portion, a flat article in the package having part accommodated in and protected on both sides by said lower fold, and another flat article in said package having part accommodated in and protected on both sides by said upper fold portion whereby with the index finger of one hand inserted in said pleat and with other fingers of the same hand engaging the outside of said fold portions the articles are individually gripped in the fingers while the tearing flap is being pulled by the other hand to open the top of the package.

4. A package comprising a rear panel of paper having upper, lower and side edges and having a first top panel portion folded over from said upper edge and having a sealing flap intermediate the depth of the package, means connecting side edges of said bottom panel to corresponding edges of said first top panel portion, superimposed relatively flat articles on said rear panel having upper portions covered by said first top panel portion, a second top panel portion closing the rest of the top of the package and having a lower edge and having a flap opposite said lower edge secured to said sealing flap, a connection between said lower edge of said bottom panel and said lower edge of said second top panel portion including an inwardly projecting pleat extending between and separating lower portions of the flat articles whereby with the index finger of one hand inserted in said pleat, and with other fingers of the same hand engaging the bottom and top of the package, the flat articles are individually gripped while the other hand is ripping open the package by an upward pull on said tearing flap, the side edges of said pleat being sealed to the adjacent side edges of the top and bottom panels.

5. The method of wrapping superimposed flat articles comprising placing said articles on a portion of an elongated paper sheet intermediate the length of the sheet and forming a back panel, folding an upper portion of the sheet over the upper edges of the superimposed articles and downwardly part way over the articles leaving a tearing flap portion, folding a lower portion of the sheet inwardly for a limited distance between the lower portions of the articles, outwardly again, and then over the top of the uppermost article a limited distance to meet said downwardly folded portion, and then outwardly in the form of a flap, adhesively connecting said flaps together, and adhesively connecting the side edges of the package together.
